UNITED STATES PATENT OFFICE.

CUTLER D. KNOWLTON, OF ROCKPORT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

RESILIENT MOUNTING FOR MACHINERY.

1,309,759.

Specification of Letters Patent. Patented July 15, 1919.

Application filed November 3, 1917. Serial No. 200,080.

To all whom it may concern:

Be it known that I, CUTLER D. KNOWLTON, a citizen of the United States, residing at Rockport, in the county of Essex and State of Massachusetts, have invented certain Improvements in Resilient Mountings for Machinery, of which the following description, in connection with the accompanying drawings, is a specification, like reference characters on the drawings indicating like parts in the several figures.

This invention relates to trimming machines and it is disclosed as embodied in a machine for trimming shoes. The general object of the invention is to provide means for eliminating the undesirable and destructive vibration characteristic of various high speed machines, which will be especially well adapted for application to machines such as machines for trimming the sole edges of shoes without any sacrifice of their utility.

It has been found that sole edge trimming machinery is singularly sensitive to vibration. Under the present practice the shoe is freely held in the hand of the operator, who determines the depth and direction of cut by eye, and even a slight degree of vibration in the machine will cause a wavy effect to appear on the sole edge, damaging the shoe.

This difficulty has led to the installation of braces on such machines running to elements of the building in which the machine is placed in order to minimize the vibration arising in the machine. It has become the custom to send out several turnbuckles for braces as regular equipment of certain machines, and it is a very general custom among operators to add more. Machines have been found to which the trimmer had attached more than fifteen braces running to floor, walls and ceiling.

Moreover, shoe manufacture is frequently conducted in old or wooden buildings, which are too lightly constructed to accommodate to the best advantage the machinery placed in them, and it has been found that no matter how accurately a machine may be balanced, enough vibration is communicated to it in many buildings through the floor to preclude the accuracy of the trimming operation. It is also true that an improperly bal-

anced machine will transmit its own vibration through an unstable building to other machines.

It is a particular object of my invention to provide satisfactory means for eliminating vibration from every such source and an important feature of the invention is a novel shock absorbing mounting for the machine to absorb the vibration transmitted from the building, or arising in the machine, and to obviate need of braces or the like.

Another feature consists in constructing and arranging this mounting for the machine so as to be resilient in the direction of maximum vibration of the element of the building to which the machine is attached. The machine shown is also comparatively non-resiliently connected with the element in the direction of minimum vibration thereof so that free independent vibration cannot be set up in the machine in this direction.

Another feature resides in means for damping out vibrations existing in or transmitted to the machine. In the machine shown, the resilient mounting contains friction members which quickly consume any vibrational energy that may be transmitted to it.

Another important feature resides in a mounting for the machine which is resilient in one direction and is arranged to divert a shock in a transverse direction into the direction of resilience, so that the energy of the diverted shock will be consumed by the resilient structure. It is thus possible to absorb energy of shock coming to the mounting in any direction without sacrificing the advantages inherent in rigidity.

These and other features of the invention comprising certain arrangements and combinations of parts will be best understood from the following description of a preferred embodiment thereof, selected for purposes of illustration and shown in the accompanying drawings in which,

Figure 1 is a side elevation, and

Fig. 2 is a detail of the vibration absorbing mechanism.

The base 10 carries a column 12 having a counter-shaft 14 carrying two pulleys 16, 18 which drive the forepart and shank cutter shafts 20, 22 respectively. The counter-

shaft 14 is connected by a double universal joint 24 with a driving shaft 26 carrying tight and loose pulleys 28, 30 respectively. This shaft is mounted in a bracket 32 attached to the floor.

The base 10 is resiliently mounted on the floor. A sub-base 34 rests on the floor and the sub-base 34 and the base 10 have a convenient number of opposed concave seats 36 in each pair of which are mounted a pair of clam-shell-like members 38. The exterior surfaces of the members 38 fit the concave surfaces of the seats 36, which are preferably spherical.

15 The two opposed members 38 may be hinged together as at 40, and a spiral spring 42 is mounted between them in seats 44. The trimming machine is therefore supported conjointly by hinge pins 40 and the 20 springs 42, and the transmission of vibration to the machine from the structure of the building itself is materially reduced. The joint at 24 prevents the slight relative movement which takes place between the 25 floor and the machine from interfering with the transmission of rotation to shaft 14.

When the floor to which the machine is fastened is subject to vertical vibration, or when vertical vibration is set up in the 30 machine, the members 38 open and close about the hinge 40, the spring 42 lengthening and shortening. At the same time, the members 38 slide slightly on the seats 36. The friction at these surfaces and the molecular 35 friction in the springs absorb and damp out the vibrational energy, and the resilience largely prevents the transmission of the vibration between the floor and machine.

Horizontal vibrations in floors are not to 40 be expected to any marked extent, and a more nearly rigid connection in the horizontal direction is therefore permissible. A horizontal jar will cause the two members 38 to rotate slightly as one member, sliding 45 on the seats 36. This movement raises the base 10 slightly but the machine tends to settle back into a normal position, and the friction on the seats 36 consumes much of the energy of the shock. Relative movement 50 of the members 38 toward or from each other will have a small component of horizontal relative movement of the bases 10 and 34, since such a movement changes the composite shape of the members 38. This 55 component will, however, be very small. The horizontal resilience of the mounting is therefore considerably less than its vertical resilience. The relative vertical movement of the bases resulting from the horizontal shock will be absorbed partly by friction and partly by the springs in their direction of maximum effectiveness, so that the mounting diverts a portion of a horizontal shock into a vertical direction and 60 destroys the energy of the vertical compo-

nent, without entirely sacrificing the advantage of considerable rigidity in mounting. The action is similar to that of a pendulum suspension consisting of a spiral spring. A vertical jar to the point of suspension is largely damped out by the spring and does not reach the pendulum bob. A horizontal jar to the point of suspension raises the pendulum slightly and is partly thus transformed into a vertical jar which 70 is damped out by the spring. The pendulum bob, however, has no horizontally rigid connection whatever with its point of support, whereas the present horizontal connection has considerable rigidity.

Having described my invention, what I claim as new and desire to secure by Letters Patent of the United States is:—

1. A mounting for machinery, comprising a machine base having a plurality of inverted segmental spherical cups in its bottom surface, a resilient load-sustaining spheroidal unit arranged in each of said cups, and a plurality of segmental spherical cups sustaining said units respectively. 85

2. A mounting for machinery, comprising a machine base having a plurality of inverted cups in its bottom surface, a plurality of load-sustaining cups arranged in registration with said inverted cups respectively, 95 and resilient load-sustaining units each arranged in a registering pair of said cups and conforming to each cup of the pair to maintain the base yieldingly against lateral displacement.

3. In combination, a machine frame, a resilient means arranged to support the frame and absorb vibrations, a rotary driving element supported otherwise than by said frame, a rotary driven element supported 105 by the frame, and universally jointed transmission means connecting said driving element and driven element.

4. A mounting for machinery, comprising the combination with supporting means, 110 of a plurality of load-sustaining units arranged to rest separately on said means, and a machine base arranged to rest on said units, the latter having convex surfaces where they engage said means and the base, 115 and said means and base having concave surfaces engaging and conforming to said convex surfaces, whereby horizontal vibrations are diverted toward vertical lines, said units being resilient in vertical lines. 120

5. A mounting for machinery, comprising the combination with supporting means, of a plurality of load-sustaining units arranged to rest separately on said means, and a machine base arranged to rest on said units, the 125 load sustaining surfaces of said means, said units and said base being arranged to slide, one on another, to offer frictional resistance to relative horizontal movement, said frictional surfaces being arranged, furthermore, 130

to divert horizontal vibrations toward vertical lines, said units being resilient in vertical lines.

6. A mounting for machinery, comprising the combination with supporting means, of a plurality of load-sustaining units arranged to rest separately on said means, and a machine base arranged to rest on said units, each of said units comprising an upper section, a lower section, a hinge member connecting said sections, and a spring arranged to coact with said sections to sustain the load, said means, said units and said base having co-active surfaces formed to utilize said springs to absorb vibrations in substantially horizontal lines.

7. A mounting for machinery, comprising the combination with supporting means, of a plurality of load-sustaining units arranged to rest separately on said means, and a machine base arranged to rest on each of said units, the load-sustaining surfaces of said means, said units, and said base being otherwise than plane and being counterparts of each other, whereby each of the units, independently of the other or others, is caused to maintain lateral registration of the base relatively to the supporting means and each of said units being resilient in substantially vertical lines.

8. A mounting for machinery, comprising the combination with supporting means, of a plurality of load-sustaining units arranged to rest separately on said means, and a machine base arranged to rest on each of said units, each of said units comprising two segmental spherical sections capable of relative movement, and a spring arranged to coact with said sections to sustain the load, said means and said base having cavities in which said sections, respectively are seated.

9. A mounting for machinery, comprising the combination with supporting means, of a plurality of load-sustaining units arranged to rest separately on said means, and a machine base arranged to rest on each of said units, each of said units comprising two segmental spherical sections, a hinge member connecting them, and a spring arranged to coact with said sections to sustain the load, said means and said base having segmental spherical cavities in which said sections, respectively, are seated.

10. A mounting for machinery, comprising the combination with a machine base and a support therefor, of a plurality of resilient load-sustaining units arranged between the base and the support so that each unit will function independently of another, the base and support having shoulders engaging said units and arranged to utilize the latter to maintain the base against lateral displacement.

11. A machine of the class described having a base and a sub-base which have a pair of opposed spherical seats, a pair of hinged members fitting said seats and a resilient member interposed between the hinged members.

12. A mounting for machinery, comprising the combination with a machine base and a support therefor, of a plurality of resilient load-sustaining units arranged between the base and the support so that each unit will function independently of another, the base and support having cups in which said units are arranged, whereby the base is maintained against lateral displacement.

In testimony whereof I have signed my name to this specification.

CUTLER D. KNOWLTON.
